MAGNETIC HEAD FOR TAPE RECORDERS

Hiroshi Muraoka, Tokyo, Japan, assignor to Pioneer
Electronic Corporation, Ohtaku, Tokyo, Japan

Filed Dec. 16, 1971, Ser. No. 209,006

Term of patent 14 years

Int. Cl. D14—01, 99
U.S. Cl. D26—14 B

FIG. 1

FIG. 2

FIG. 3

FIG. 4

FIG. 1 is a top, perspective view of a magnetic head for tape recorders showing my new design;

FIG. 2 is a bottom, perspective view from the opposite side thereof;

FIG. 3 is a front elevational view thereof; and

FIG. 4 is a top plan view thereof.

I claim:

The ornamental design for a magnetic head for tape recorders, as shown.
